Primary Examiner—Prabhakar Deshmukh
Attorney, Agent, or Firm—Wood, Herron & Evans[57] **CLAIM**

The ornamental design for a two layer can carton, as shown and described.

DESCRIPTION

FIG. 1 is a perspective view of a two layer can carton showing our new design;

FIG. 2 is a top view of the can carton shown in FIG. 1;

FIG. 3 is a front view thereof, the rear view being a mirror image;

FIG. 4 is a right side view thereof, the left side view being a mirror image;

FIG. 5 is a bottom view thereof;

FIG. 6 is a top view of the carton blank, the bottom view being a mirror image thereof;

FIG. 7 is a side view thereof, the other side being a mirror image thereof;

FIG. 8 is a right end view thereof of the design; and,

FIG. 9 is a left end view thereof.
